UNITED STATES PATENT OFFICE.

PHINEHAS D. DUNN AND CHARLES W. DUNN, OF CLEVELAND, OHIO.

MACHINE FOR SETTING AND GUMMING SAWS.

SPECIFICATION forming part of Letters Patent No. 284,192, dated September 4, 1883.

Application filed December 4, 1882. (No model.)

To all whom it may concern:

Be it known that we, PHINEHAS D. DUNN and CHARLES W. DUNN, of Cleveland, in the county of Cuyahoga and State of Ohio, have 5 invented certain new and useful Improvements in Combined Saw-Set and Saw-Gummer; and we do hereby declare the following to be a full, clear, and exact description of the invention, such as will enable others skilled in the art to

10 to which it pertains to make and use the same.

Our invention relates to improvements in a combined saw-set and saw-gumming machine; and it consists of parts and combinations of parts more fully hereinafter described and 15 claimed.

In the drawings, Figure 1. is a view in perspective of our device. Fig. 2 is a side view of the same. Figs. 3, 4, and 5 are views in detail of the same device.

20 A represents a standard, a branch of which forms the sloping arm *a*, provided with the thumb-screw *a'*. The standard is provided with a mortise, commencing at the junction of the arm and extending upward, the top head 25 of the mortise forming a knife-edge, as at *a*². The top *a*³ of the standard is made in shape of a tenon, the shoulders on either side terminating in a knife-edge, as shown at *a*⁴.

B represents a lever with a forked end. 30 These forks extend on either side of the tenon *a*³, and rest and are fulcrumed on the knife-edges, as at *a*⁴, and are held from lifting by the pin *b*. These forks extend also on either side of a narrow part or tenon on the bar C, 35 the shoulders of which terminate in knife-edges, as at *c* and *c'*, coming in contact with the top and bottom of the forks of the lever B. The ends of said forks are provided with the pin *b'*, holding the bar C in position. The 40 lower end of the bar C is provided with a mortise that, when the parts are in position, comes opposite the said mortise in the standard. The ends of this mortise terminate in the knife-edges *c*' and *c*'. In Fig. 2 the sides 45 of the standard and the bar are broken away at this part to show the inside of the mortise.

D represents a tool, one end of which, as at *d* in the side view, Fig. 3, is made in suitable shape for gumming saws. The other end, as 50 shown at *d*' in the top view, Fig. 4, is made suitable for saw-setting. This tool is operated in the said adjacent mortises, and is held

in position by the loose-fitting pins *d* and *d*'. The said tool is reversible endwise, and is fulcrumed on the knife-edge *a*². Directly under 55 the front end of the tool D, at E, is a vertical hole for the insertion of dies, and has a smaller hole at the bottom for forcing out the dies with a punch. The faces of these dies are made of any desired shape suitable for gumming or 60 setting saws.

The lever F is fulcrumed on the set-screw *f*, attached to the standard, and is attached to the bar C by the thumb-screw *f*', operating in a slot in the lever F. On the opposite side of 65 the standard from the lever F is attached the gage G (shown also in Fig. 5) by a thumb-screw passing through the slot *g*, the sides of the notch *g*' coming on either side of the front end of the tool D. 70

H represents a spring for raising the handle end of the lever B.

The operation of our device is as follows: The tool D is first placed in position with the end desired for use in front on the die at E. 75 The saw is then placed in position, as at I, with the teeth-edge under the point of the tool D, and the blade of the saw resting on the end of the thumb-screw *a'*, by which the saw is adjusted at the required incline. Next the gage 80 G is adjusted to admit of the teeth of the saw extending the desired distance under the tool D. By pressing down on the handle of the lever B, and by means of the fulcrum aforesaid, and by means also of the connections with 85 the bar C, as aforesaid, the front end of the tool D is pressed down on the saw for gumming or setting, and at the same time the foot of the lever F is pressed upon the saw, holding it firm while the tool D is doing its work. When 90 the said handle is raised, the front end of the lever F and of the tool D are also raised, leaving the saw free to be moved along and made ready for the operation to be repeated.

It will be seen that the great pressure brought 95 to bear on the fulcrums of the lever B and the tool D, and also on the attachments of the said lever and said tool with the bar C, are all on the said knife-edges, instead of on the pins.

What we claim is—

1. In a combined saw-set and saw-gumming machine, the combination, with a saw-support and an operating-lever, of a saw setting and gumming tool connected to said lever by a bar,

and a saw-clamp adapted to be operated simultaneously with the tool by means of said lever and connecting-bar, substantially as set forth.

2. In a combined saw-setting and saw-gumming machine, the combination, with the standard A and lever B, of the tool D and the bar C, connected with said tool and lever by knife-edge pivots, substantially as described.

3. The combination, with the standard A, saw-support a, and lever B, of the tool D, arranged through a slot in said standard, the bar C, pivotally connected with said lever and tool,

and the clamp F, pivoted on the standard and connected with said bar for operation thereby, substantially as described.

In testimony whereof we sign this specification, in the presence of two witnesses, this 23d day of November, 1882.

PHINEHAS D. DUNN.
CHARLES W. DUNN.
